UNITED STATES PATENT OFFICE.

ABBOTT L. COMBES, OF WASHINGTON, DISTRICT OF COLUMBIA, ASSIGNOR OF ONE-HALF TO HARRY M. KEYSER, OF EAST FALLS CHURCH, VIRGINIA.

RIPPING UNIT FOR METAL CANS.

Application filed May 7, 1928. Serial No. 275,617.

This invention relates to an improved ripping unit for metal cans of the character prevalently employed in canning food stuffs or the like and seeks, among other objects, 5 to provide a ripping unit for use in connection with the conventional can lid without necessitating change in the basic structure of the lid or the can to which the lid is to be applied.

10 The invention seeks, as a further object, to provide a ripping unit which may be attached to and handled along with the can lid and secured in proper position within the can body by the usual machinery now employed for handling the lid alone and crimping the lid in position.

15 A further important object of the invention is to provide a ripping unit having novel means for connecting said unit with the can lid and firmly holding the unit in proper position thereon.

20 And the invention seeks, as a still further object, to provide a device which may be manufactured and installed at feasibly low cost.

25 Other objects of the invention not specifically stated in the foregoing will appear during the course of the following description.

In the drawings,

30 Figure 1 is a fragmentary perspective view showing a conventional can and lid with my improved ripping unit installed,

Figure 2 is a detail perspective view of the assembled lid and ripping unit, partly broken away and shown in section,

35 Figure 3 is a detail perspective view of the ripping unit, partly broken away and shown in section,

Figure 4 is an enlarged fragmentary sectional view showing the ripping unit in process of being applied to the lid.

40 Figure 5 is a fragmentary perspective view showing the ripping unit fully applied to the lid and illustrating a portion of the upper part of the body of the conventional can as it appears before lid is applied.

45 Figure 6 is a fragmentary longitudinal sectional view through the ripping unit and can lid at the point where one end of the ripping unit is anchored and the other end thereof is led out of its retaining sleeve and through the can lid,

50 Fig. 7 is a fragmentary sectional view similar to Figure 5 but showing a slight variation of the invention, and,

Figure 8 is a fragmentary sectional view 55 showing a further slight variation of the invention.

In carrying the invention into effect, I employ a carrier ring 10 which, in the present instance, is endless, although if desired, said ring may be formed from a strip of metal and its two ends joined together or left unjoined. The ring 10 is preferably formed of suitable resilient sheet metal, of a light gage, and is bent at its outer margin to provide an 60 annular channel 11 having an outer annular side flange 12. As seen in Figure 4, the outer side flange 12 of said channel is somewhat shorter than the inner side wall 13 of the channel, and projecting radially inward from 65 the side wall 13 is a horizontally disposed annular lip 14. The inner margin of the lip 14 is bent to form a tubular sleeve 15, and enclosed in said sleeve is a ripping element 16 70 preferably of suitable resilient wire. As best 75 shown in Figure 6, one end of the ripping element is bent to form a hook 17 anchored through the bottom wall of the sleeve, while the opposite end of said element is extended upwardly to provide a free terminal 18. The 80 ripping element is thus firmly connected with the carrier ring to form a ripping unit and, as will be observed, the sleeve 15 completely 85 encloses the ripping element for excluding juices or other contents of a can in connection with which the device is used.

In the drawings I have shown a conventional can body at 19 which, as seen in Figure 5, is provided at its open end with the usual out-turned annular flange 20. A conventional lid is shown at 21. As is usual this lid is bent to provide an annular reinforcing rib 22, while at its outer margin the lid is provided with an annular down-turned channel 23 having a straight inner side wall 24 and an outer side flange 25 curving inwardly towards the base of the wall 24. As will be observed, a flat annular area 26 is defined between the rib 22 and the inner side wall 24 of the channel 23, this channel being 95 of a width and depth to freely receive the flange 20 of the can body 19. Normally, the lid is positioned upon the can body so that the flange 20 is seated in the channel 23 when 100 said flange and the flange 25 at the periphery 105 of the lid are crimped, as indicated in Figure 1 at 27, in the usual manner for connecting the lid with the can body.

In accordance with the present invention, the ripping unit shown in Figure 3 is installed upon the lid before the lid is applied to the can. As best shown in Figures 4 and 5, the side wall 13 of the channel 11 of the carrier ring is of a diameter to more or less snugly surround the inner side wall 24 of the channel 23 of the lid, so that assembly of the ripping unit upon the lid may be accomplished simply by pressing on the ripping unit to push the channel of the carrier ring into the channel of the lid. Figure 4 shows the ripping unit partially applied, and attention is now directed to the fact that, as the outer 10 side flange 12 of the channel 11 of the carrier ring moves across the free edge of the outer side flange 25 of the channel of the lid, the flange 12 is flexed or contracted slightly. Consequently, as the top wall of the channel 11 moves into abutting relation to the top wall of the channel 23 and the free edge of the side flange 12 clears the free edge of the side flange 25, the flange 12 will, as shown in Figure 5, expand and snap into engagement 15 with the lower inner margin of the flange 25 for rigidly locking the ripping unit upon the lid. Coincident with the application of the ripping unit to the lid, the terminal 18 of the ripping element is inserted through a suitable opening in the lid so that the carrier ring may seat throughout the major portion of its area, flat against the under side of the lid. The flange 12 of the carrier ring will thus coact with the flange 25 of the lid for firmly locking the ripping unit upon the lid so that the lid may be freely handled without fear of accidental loss or detachment 20 of the ripping unit. As brought out in Figure 5, the channel 11 of the carrier ring is of an internal diameter at the top wall thereof to freely receive the flange 20 of the can body 19. Accordingly, the lid, with the ripping unit thereon, may be handled by the usual machinery now employed for handling the lid alone and the lid with the ripping unit thereon may, likewise, be crimped upon the can body by the usual machinery now employed for crimping the lid alone. Under this latter operation, the flange 12 of the channel 11 of the carrier ring is interfolded 25 with the flange 20 of the can body and the flange 25 of the lid for rigidly securing the ripping unit upon the can body at the same time the lid is attached thereto. Normally, the inner face of the top wall of the channel 23 of the lid is covered with a sealing cement and preferably, a like coating of cement is applied to the inner face of the top wall of the channel 11 of the carrier ring, so as to form a sealed joint with the can body. Either before or after the lid is applied in the manner indicated, the opening through the lid which accommodates the terminal 18 of the ripping element is closed with solder 30 and, preferably, a suitable key as indicated

at 28 is attached to said terminal so that the key will always be at hand for opening the can.

To open the can, the key 28 is disposed to extend across the upper edge of the crimp 27 of the can, when the key is turned for winding the ripping element 18 thereon. As the winding operation progresses, the ripping element is drawn upward thus opening and releasing itself from the sleeve 15 of the carrier ring and cutting or severing the lid in a circular path coincident with the winding operation. The can may thus be readily opened.

At this juncture attention is directed to the fact that the lip 14 of the ripping unit is of a width to support the ripping element medially of the flat area 26 of the lid. This particular placing of the ripping element is made in order to accomplish three definite objects that are necessary to uniformly successful operation of the device—to wit:—

1. Removes the terminal 18 of the ripping element away from the side wall 24 of the lid, thus preventing its interfering with the chuck of the machine used to attach the lid to the can. 2. Removes the line of severance of the lid to a location on the flat area 26 where the ripping element in process of opening the can cannot be fouled by running up between the side walls 13 and 24. 3. Defines and maintains the line of severance of the lid at a location where the metal of the lid is easiest to sever by virtue of being flat and free from special curved and angular shapes which materially increase the resistance to severance by a wire ripping element.

In Figure 7 of the drawings, I have shown a slight variation of the invention. In this figure, a conventional lid is indicated at 29 and a ripping unit at 30. This ripping unit is identical with the ripping unit first described, with the exception that the outer side flange 31 of the channel 32 of the carrier ring of said element is somewhat narrower than the flange 12 of the carrier ring 10. Accordingly, when the ripping unit of Figure 7 is applied to the lid, the flange 31 will, as shown in full lines, initially clear the free edge of the outer side flange 33 of the channel 34 of the lid. The flange 31 is, therefore, subsequently bent or straightened to the dotted line position shown in Figure 7, to impinge the flange 33 for firmly locking the ripping unit upon the lid.

In each of the embodiments of the invention previously described, the ripping unit is arranged to open the can by cutting or severing the metal of the lid. However, there are certain advantages to be had through opening a can by severing the side wall of the can body on a line immediately below the crimped joint between the can body and the lid. The present invention is adaptable for opening a can by severing the body

wall and Figure 8 shows a variation of the invention adapted to accomplish this purpose. A conventional can body is indicated at 35 and a conventional lid at 36, the lid being crimped on the can body as shown at 37. A ripping unit is employed similar to the ripping unit first described and includes a carrier ring 38, the outer margin of which is interfolded in the crimp 37 while the inner margin of said ring is bent to form an outwardly facing tubular sleeve 39 housing a ripping element 40. The sleeve 39 and element 40 are like the sleeve 15 and element 16 of the ripping unit shown in Figure 3 with the exception that the sleeve 39 abuts the body wall of the can body 35 and that the mouth of the sleeve faces said wall. One end of the ripping unit is arranged to extend through said body wall to provide a free terminal 41 to which a key may be attached so that, as will be well understood in view of the foregoing description, the key may be turned for winding the ripping element thereon and causing said element to sever the body wall of the can.

In the present instance, I have shown the invention in conjunction with a cylindrical can. However, as is well known cans of other shapes are employed for canning food stuffs and the like, and in any such instance, the ripping unit will be shaped to conform to the contour of the can. The term "carrier ring" as herein used shall, therefore, be construed to comprehend such variations in shape.

Having thus described the invention, I claim:

1. As a new article of manufacture, a ripping unit including a carrier ring having a ripping element thereon and provided with means to coact with the peripheral margin of an unattached can lid for connecting the ring with the lid to lie at the under side thereof.

2. As a new article of manufacture, a ripping unit including a carrier ring having a ripping element thereon and provided with a peripheral flange to coact with the peripheral flange of an unattached can lid for securing the ring upon the lid at the under side thereof.

3. The combination with an unattached can lid having a peripheral flange, of a ripping unit disposed at the under side of the lid and including a carrier ring having a ripping element thereon operable to open a can to which the lid may be attached, said

ring being provided with means to coact with said flange for securing the unit upon the lid.

4. The combination with an unattached can lid having a peripheral flange, of a ripping unit disposed at the under side of the lid and including a carrier ring having a ripping element thereon operable to open a can to which the lid may be attached, said carrier ring being provided with a peripheral flange disposed to coact with the flange of the lid for securing the ripping unit upon the lid.

5. The combination with a can body having a peripheral flange, and a lid attached to the can body at one end thereof to form a closed can, the lid being provided with a peripheral flange interfolded with the flange of the can body for securing the lid upon the body, of a ripping unit carried by the lid and including a carrier ring disposed at the under side of the lid and having a ripping element operable to sever a wall of the can, the carrier ring being provided with a flange disposed to coact with the flange of the lid when unattached for initially securing the ripping unit upon the lid and being interfolded with the flanges of the lid and can body for rigidly securing the ripping unit in operative position.

6. The combination with an unattached can lid provided near its periphery with a channel, of a ripping unit carried at the under side of the lid and including a carrier ring having a ripping element operable to open a can to which the lid may be attached, said ring being provided near its periphery with a channel locked in the channel of the lid for connecting the ripping unit with the lid.

7. The combination with an unattached can lid provided near its periphery with a reinforcing rib and in spaced relation to said rib with a peripheral channel, the lid being formed with a flat area between said channel and rib, of a ripping unit carried at the under side of the lid and including a carrier ring having a ripping element thereon and provided near its periphery with a channel locked in the channel of the lid for connecting the ripping unit with the lid, said ring supporting the ripping element in juxtaposition to said flat area of the lid whereby said element may be operated for severing said area.

In testimony whereof, I hereunto affix my signature.

ABBOTT L. COMBES. [L. S.]
